SELECTION MECHANISM FOR TEN-KEY MULTIPLIER CONTROL UNIT

Harold J. Chall, San Leandro, and Arthur J. Malavazos, Oakland, Calif., assignors to Friden, Inc., a corporation of California

Application October 13, 1953, Serial No. 385,766

10 Claims. (Cl. 235—63)

This invention relates to calculating machines, and more particularly to an improved selection mechanism for inserting values into a multiplier control unit of the type shown and described in the patent to Carl M. Friden, No. 2,371,752, issued March 20, 1945.

A primary object of the present invention is to provide a selection mechanism for a ten-key machine, such as the multiplier mechanism above mentioned, which eliminates the resetting combs heretofore conventional in this type of mechanism.

Another important object of the present invention is to provide what is sometimes called a "flexible ten-key keyboard," i.e., a selection mechanism in which a value is set by the depression of a value key, which value remains latched in the mechanism until another key is depressed in that same order, the depression of the second key in the order causing the release of the first value and the insertion of the second.

Still a further object of the present invention is to provide a ten-key selection mechanism particularly adaptable for repeat operations, i.e., a series of operations in which the value is maintained for a plurality of different problems, or operations; it being conventional in the past to provide a selection rack in two portions, one of which was latched for a repeat operation while the other was rotated during the operation to control digitation and then returned to the first portion by a suitable spring.

Another important object of the present invention is to provide a selection mechanism for a multiplying unit of the type described, which is simpler and more economical to assemble than that conventional in the art.

These and other objects of the present invention will be apparent from the specification and claims which follow, both of which will be more readily understood by reference to the drawings which form a part hereof and in which:

Fig. 1 is a plan view of a machine of the type described in said Friden patent, with a portion of the cover broken away to show some of the mechanism involved in the instant invention.

Fig. 2 is a right side view of the multiplier selection unit with which our invention is associated.

Fig. 3 is a front view of the pin carriage of our invention, such as taken along the oblique plane indicated by the line 3—3 of Fig. 2.

Fig. 4 is a left side view of the mechanism shown in Figs. 2 and 3.

Fig. 5 is a plan view of a portion of the multiplier mechanism such as taken along the horizontal plane indicated by the line 5—5 of Fig. 4.

Fig. 6 is a front view of the mechanism shown in Fig. 5.

Fig. 7 is a rear view of the escapement mechanism associated with the pin box, or carriage, such as one taken along the oblique plane indicated by the line 7—7 of Fig. 2.

Fig. 8 is a perspective view of one of multiplier unit digit keys associated with our invention.

2

Fig. 9 is a perspective view of one of the selection levers, intermediate the keyboard and the pin carriage of the multiplier mechanism.

Our invention is preferably associated with the multiplication mechanism shown and described in the above-mentioned patent to Friden No. 2,371,752. In fact, the present invention discloses certain improvements in the mechanism there shown and described. The commercial machine manufactured in accordance with the teachings of said patent has been modified in certain particulars not here pertinent, to follow the teachings of the patents to Friden, et al., No. 2,376,997, of May 29, 1945 and No. 2,399,917, of May 7, 1946. In view of the similarity of the present mechanism to that shown in the patent first mentioned, it is deemed unnecessary to describe the complete machine in detail. Therefore, only so much of that machine as is essential to an understanding of the present invention will be described, and for a full understanding of the operation of the complete machine one is referred to that patent.

It should be noted at the outset that the present invention relates to certain improvements in the multiplier unit of that patent, and particularly to a simplified construction of the pin carriage and the associated selection racks which form a portion of the selection mechanism of that machine.

The complete machine is shown in Fig. 1, and comprises a full, or 100 key, keyboard 20 which is supported between right frame plate 21 and left frame plate 22. The keyboard 20 controls a selection mechanism, not shown and not pertinent to the present invention, which cooperates with cyclically operated actuators, likewise not shown, to enter values additively or subtractively into an accumulator register 24 which is mounted in a shiftable carriage 25. The carriage also has a counter, or quotient register, 26 which is operative to count the cycles of operation, and in multiplication operations will normally show the multiplier at the end of the operation.

To the left of the front portion of the keyboard 20 is a multiplier keyboard 30 which is supported between the left frame plate 22 and left side control, or auxiliary, plate 23. The keyboard 30 is of the ten-key type, having ten value keys for the "0" and values "1" to "9," inclusive, which are operative to enter values into a multiplier mechanism order by order, beginning with the highest. The machine is preferably provided with a window 31 through which check dials showing the multiplier digits, can be seen.

It can be noted that the machine is provided with certain multiplier control keys adjacent to, and surrounding, the multiplier keyboard 30. However, these control keys operate in the manner shown in the patents mentioned, and have nothing to do with the instant invention, which relates specifically to the selection mechanism of the multiplier unit. The mechanisms operated by these control keys are not shown and described in the instant application. It can also be noted that there are a number of operation control keys to the right of the main, or full, keyboard 20, which likewise are not described, for they operate in a conventional manner and have no connection with the present invention.

Our invention relates to the selection mechanism of the multiplier unit, which mechanism includes the keys 30; a multiplier carriage which includes a plurality of orders of settable pins and an actuating rack associated with each order of pins; and interponent levers for setting the pins from the depression of the keys 30. The keyboard 30 and the assembly associated therewith are of conventional construction, but because of their close association with the selection mechanism of our invention, will be described in some detail. As shown in Fig. 1, the multiplier keys 30 from "1" to "9" are arranged

in a square 3 x 3 relationship, with the "0" key located in front of the value keys. The keys 30 are mounted upon key stems 32 (see Figs. 2 and 8), each of which key stem is provided with a laterally offset portion 33 and spaced guide portions 34 and 35, preferably extending in planes at right angles to each other. The guide extensions 34 are continuations of the key stem 32 proper, while the extensions 35 project downwardly from the offset portions 33 so as to be symmetrically staggered along a central longitudinal axis of the keyboard 30. The key stems 32 are slidably mounted in a frame comprising an upper plate 36 and a lower plate 37 which are tied together by suitable spacing members, not shown, and which are rigidly mounted on the frame plates 22 and 23.

It can be noted, as shown in Fig. 2, that the upper portion of the key stem 32 extends through suitable slots, or apertures, not shown, in the upper plate 36, while the guide stems 34 and 35 extend through similar apertures, not shown, in the lower frame plate 37, and the lateral portions 33 lie intermediate the two plates. The keys and their associated stems are normally biased to their upper position by suitable springs 38 compressed between the lower frame plate 37 and the lateral extensions 33. The lateral extensions 33 are bent so that their outer ends are in parallel aligned relation for operating the multiplier escapement mechanism which will be described briefly hereafter (and which is fully shown and described in the patent above-mentioned). Fig. 8 illustrates the "4" value key. It will be understood that the formation of the lateral extensions 33 of the other keys differs somewhat from that shown in this figure, but that all of them are provided with a nose portion 39 lying in a longitudinal plane extending between the "2," "5" and "8" keys on the left and the "3," "6" and "9" keys on the right so as to overlie the escapement control bar 160 shown in Fig. 7. The guide stems 35 are aligned in a staggered fashion along a substantially longitudinal axis for operation with the noses 53 of the interponent, or selection, levers shown particularly in Fig. 9, as is fully shown and described in said patent. In the patent referred to, the "9" multiplier key 30 was not provided with a guide stem 35 because the "9" key was used only to operate the escapement mechanism which, in turn, released the selection racks 100, but did not set a selection pin 81, as the rack was allowed to travel until it abutted against a "9" stop bar 94. However, in our invention the "9" key is provided with a guide stem 35 which overlies a small bellcrank lever 92 for the purposes hereinafter described.

Associated with the multiplier value keys 30 are a series of eight interponent, or selection, levers 50, one of which is illustrated in Fig. 9. These levers correspond to the values "1" to "8," inclusive, none being needed for a "0" selection, as in that event the selection racks 100 are not released for it is only necessary to operate the escapement mechanism; and none is required for a value of "9," as it is only necessary to release the rack 100 through the escapement mechanism and to operate the bellcrank 92 in order to release the ordinal pin latch to be described shortly. These interponents, or selection, levers 50 are operated by their respective keys to lift one of the setting pins 81. For this purpose the interponent levers 50 are mounted on a common shaft 51 in abutting relationship. Each lever is provided with a forwardly extending arm 52 on the forward end of which is a nose 53 that underlies the guide stem 35 of the associated value key 30, these arms 52 being of different lengths. Thus, depression of any of the value keys will be operative to rock the corresponding interponent lever 50. Each of the selection levers 50 is also provided with a downwardly and rearwardly extending nose 54 which is effective to set the selection pins, as later described. The respective noses 54 lie in a guide slot 55 in the guide plate 56 rigidly mounted between the frame plates 22

and 23, in order to hold the noses 54 in a single ordinal plane, against lateral displacement. The levers are resiliently biased toward a retracted position (clockwise in Fig. 2) against a supporting bracket 57 by means of suitable springs 58 tensioned between apertures 59 in the bracket and apertures 61 in ears 60 mounted on the nose portions of the levers 50. It will be understood that depression of any of the value keys "1" to "8" will be operative to rock the associated interponent lever 50 (counterclockwise in Fig. 2) about its shaft 51, whereupon its nose 54 will engage the related value pin 81 in the aligned ordinal row of pins in the pin carriage to move the pin to an active position. It is seen, therefore, that the respective selection levers 50 are provided for the multiplier keys 30 for the values "1" to "8," respectively, and that upon depression of a key 30, the corresponding lever 50 will be rocked about shaft 51 to project its finger 54 to active pin-setting position shown in Fig. 2 as applied to the "6" key, selection lever, and related pin. In the pin carriage, eight pins are provided in each ordinal row for the keys "1" to "8," inclusive, and a fixed stop 94 is provided corresponding to the value "9." The only function of the depression of the "9" multiplier key 30 is to operate the escapement mechanism to step the shiftable selection mechanism one step to the left and to operate the aligned zero latch 110 to release the aligned rack 100 in the pin carriage, and, in our invention, to release the ordinal pin latch 88 to be described later. Neither is a pin necessary for the value "0," as the only function of the "0" key is to operate the escapement mechanism.

It will be understood that the keyboard, its frame and the associated selection, or interponent, levers 50 and plate 56 are fixedly mounted in the machine frame—there being the ten value keys and the eight selection levers as above mentioned. Associated with this fixed mechanism is a shiftable carriage, designated generally at 70. The shiftable multiplier carriage 70 comprises a pair of end plates 71, a pair of frame plates 75 and 76, the end and frame plates being held in rigid relationship by a plurality of tie bars 72. The carriage 70 is shiftable transversely on a pair of carriage rails 73 and 74, which are rigidly mounted in the left side frame and control plates 22 and 23, respectively. The frame plates 75 and 76 are provided with a plurality of ordinally arranged slots 80—there being eight such slots in each order and, in the conventional Friden machine, there are ten orders. The slots 80 are aligned in the top and bottom plates and each pair is adapted to receive a pin 81 for movement therethrough. The various pins 81, as shown in Figs. 2 and 4, are of different sizes, as shown, roughly following a circumference of the forward nose of the selection rack 100. The various pins 81 are resiliently biased downwardly by compression springs 82 which are seated in slots 83 in the lower end of the pins, the springs being compressed between the bottom of the lower frame plate 76 and the bottom portion of the slot 83. Excessive downward movement of the pins 81 is blocked by any suitable means, such as projections 84, which in the lower position of the pins 81 abut against the top of the bottom plate 76.

Each of the pins 81 is provided with a laterally extending projection 85, as shown in Fig. 3, the top of which is provided with a cam face 86, while the bottom forms an abrupt shoulder 87. Associated with the latching projection 85, in each order of the pins 81, is an ordinal latching bail 88. Each bail 88 is pivotally journaled in the multiplier carriage, as by mounting upon a shaft 89 which is pivotally mounted in the upstanding sides of the lower frame plate 76. The latching bails 88 are provided with a latching nose 90 and each is resiliently biased into engagement with the side of the pins 81 of that order by any suitable means, such as a spring 95 tensioned between a bar 96 rigidly secured to the shaft

89 and a second bar 97 mounted in the carriage 70 adjacent the bottom plate 76.

It will be seen, by reference particularly to Fig. 3, that as a pin is translated upwardly by the rocking of its associated selection lever 50, the latching bail 88 is first cammed outwardly, or away from, the pin by the cam edge 86, thereby releasing any latched pin in that order for return to its lower position; and, after full movement of the pin, then latches under the shoulder 87 to hold that pin in its upward, or effective, position. It is obvious that as any value is placed in the carriage, the proper pin in the operative order will be elevated to its effective position, in which position it will be latched by the bail 88; and that the operation of the bail by the movement of the pin will be operative to release any previously latched pins in that order. It can be mentioned again that there is no "9" pin in the carriage, as the selection rack, when a value of "9" is to be inserted in the multiplier unit, will travel to, and abut against, a stop 94 formed as a tie rod between the end plates 71. However, when it is desired to insert a "9" in one of the orders of the pin carriage, it is necessary that any previously set pin in that order be returned to its normal, inoperative, position. This clearing of the other values from the keyboard is secured by rocking the bail 88 to release any of the set pins in that order, whereupon they will be retracted to their inoperative position by the force of their respective springs 82.

A simple means for rocking the latching bail 88, by operation of the "9" key, is shown in Figs. 2, 3 and 4. This mechanism comprises a small bellcrank 92 pivoted on a small pin 93 attached to the lower plate 37 of the keyboard frame. The forward end of the bellcrank 92 extends forwardly under the lower frame plate 37 of the multiplier keyboard, and lies beneath the guide stem 35 of the number "9" key. The rearward end of the bellcrank 92 is bent so as to underlie an ear 91 of the ordinarily related latch bail 88. Thus the depression of the "9" key will be effective to operate the carriage escapement mechanism hereafter to be described, and also rock the bellcrank 92 (counter-clockwise in Fig. 2) to rock the bail 88 to its unlatching position—whereupon any set pin in that order will be retracted by the force of its spring 82 to its ineffective position. It can also be noted again that no pin corresponding to a "0" value is necessary as the depression of the "0" key will operate the escapement mechanism to cause the carriage to step one order toward the left, but will not be operative to release a selection rack 100 to be described hereafter.

The carriage 70 also carries a plurality of differentially settable elements in the form of pivoted, spring-actuated, racks 100, which are normally held in their "0" positions and which can be released to assume a differential adjustment in accordance with the pin of the associated order or row—there being one such differentially positionable rack for each order of settable pins. The racks 100 are pivotally mounted on a transverse shaft 101, the ends of which are mounted in the end plates 71. The racks 100 are resiliently biased to a fully operative position (clockwise in Fig. 2 and counter-clockwise in Fig. 4) by a suitable spring 102, one end of which is seated in an aperture 103 on hub 104 and the other end of which is seated on a transverse rod 105 rigidly mounted in the end plates 71. The hub 104 serves as a spacing member to separate the racks 100 and is preferably formed with a concave circumferential surface to hold the spring 102. The rearwardly extending portion of the rack 100 is provided with ratchet teeth 106 which control operation of the multiplying mechanism of the machine, as fully explained in the patent above-mentioned. This multiplying mechanism will not be explained herein as it is assumed that it is conventional and will operate in a conventional manner. The forward portion of each of the differentially positionable racks 100 is provided with a dial face 107 carrying the numeral characters "0" and

"1" to "9," inclusive, which dial can be viewed through the window 31 of the machine to indicate to the operator the values which have been set in the multiplying mechanism.

- 5 The selection racks 100 are held in a disabled, or "0," position by means of a latch member 110 associated with each order of the selection carriage. The latch members 110 are pivotally mounted on a transverse rod 111 mounted in the carriage 70, and are resiliently biased to a latching position (counter-clockwise in Fig. 2 and clockwise in Fig. 4) by means of a suitable spring 112 tensioned between the lower end of the latch member and one of the tie rods 72. It can be mentioned at this point that the latch member 110 is operated by the carriage escapement mechanism to be presently described, thereby releasing the ordinarily aligned differentially positionable rack 100 to the force of its respective spring 102, whereupon the rack will rotate (clockwise in Fig. 2 and counter-clockwise in Fig. 4) to a position determined by one of the set pins 81 or the "9" stop 94.

In the conventional mechanism of the patent heretofore mentioned, the rack 100 is provided with a forwardly extending nose 108 which abuts against the upper end of the latch lever 110. However, in our invention we prefer to 25 provide the rack with a live, or yieldable, nose 113. The nose 113 is integral with an arm 114 which is pivotally mounted on the rack 100 by any suitable means, such as rivet, or stud, 115. The arm 114 is formed so that the nose 113 lies in the plane of the selection rack 100 and particularly the nose 108 and its associated latching arm 110, the rear edge of the arm 114 preferably abutting the nose 108 of the selection segment. The arm 114 is resiliently held in its operative position by a suitable spring 30 116 tensioned between the arm 114 and the selection rack, and is held against lateral displacement by means of a projection 117 enclosed between a portion of the rack 100 and a laterally projecting ear 118.

In multiplying operations the racks 100 are returned from their differentially adjusted positions, step-by-step 40 with each cycle of operation, to the "0" or, ineffective, position shown. Normally it rocks the associated latch 110 slightly at this last step of operation, and is thereupon relatched in the "0" position. However, in repeat operations (i.e., when a constant multiplier factor is locked into 45 the multiplying mechanism), the latch 110 will be locked in its normal position to prevent its rocking to relatch the actuator racks 100. In that situation the live tip 113 of the actuator rack will yield, against the tension of the spring 116, thereby preventing relatching of the actuator 50 rack as it returns to its "0" position. However, in that situation the rack can return to its original differential position, for in that condition the nose 113 cannot engage the end of the latch 110, and the selection segment 100, therefore, cannot be latched in its inoperative, or "0," position. Thus, in repeat operation, a rack returns to its 55 adjusted differential position as soon as it is shifted to the right of the operating ordinal position.

The carriage 70 is strongly biased to the left, i.e., to the position in which all of the selection racks 100 are in 60 operative position to control a multiplying operation, by means of a lever 125 (see particularly Fig. 5), which is pivotally mounted on the base plate 27 by any suitable means, such as screw stud 126. The forward end of the lever 125 is pulled toward the right of the machine 65 (counter-clockwise, or to the right, in Fig. 5) by a relatively strong spring 127, which extends across the front of the machine, the right end preferably being seated in the right frame plate 21 (see Fig. 1). The rear end of the lever 125 is bent to form an upstanding portion 128, the upper end of which is slotted to receive the right frame plate 71. Thus, the force of spring 127 biases the multiplier carriage 70 to the left. In the left-hand position of the carriage all of the selection racks 100 will be in 70 operative position to control a multiplying operation, as

explained in the Patent No. 2,371,752. Normally the carriage is latched in its right-hand position in which it is ineffective to control a multiplication operation, and the means for so latching said carriage in its right-hand position and for moving it step-by-step to the left as values are inserted in the multiplier keyboard 30 will now be described.

The forward portion of the shiftable carriage 70 carries a forwardly extending rack 135 (Figs. 2, 4 and 7) which cooperates with an escapement mechanism mounted on the rear of the keyboard frame, and shown particularly in Fig. 7. The rack 135 has a plurality of ordinally spaced teeth, as shown particularly in Fig. 7. Movement of the carriage 70 to the left (to the right in Fig. 7) is blocked by means of a holding pawl 136. The holding pawl 136 is in the form of a bellcrank, and is pivotally mounted on a stud 137 supported by a bracket 142 integral with the bottom frame plate 37. The pawl 136 is resiliently biased to engaging position by a spring 138 tensioned between the arm 139 of the bellcrank, and arm 155 of stepping pawl 150. The pawl 136 is provided with an integral nose 140 shaped to form blocking engagement with the teeth of rack 135 on the right end thereof (left end in Fig. 7) in order to block leftward movement of the carriage 70. The inner, or left-hand, side of the nose 140 is formed with a cam face 141, so that the pawl 136 will be rocked out of engagement with the rack when the carriage 70 is returned toward the right (to the left in Fig. 7).

A stepping pawl 150 is associated with the holding pawl 136. The stepping pawl 150 is also in the form of a bellcrank pivoted on a stud 151 supported by a bracket 152 integral with the bottom frame plate 37. The holding pawl 136 and the stepping pawl 150 lie in immediately adjacent planes and cooperate to control the step-by-step movement of the carriage toward the left (right in Fig. 7). The stepping pawl 150 carries an ear 153 bent into the plane of the holding pawl 136 and the teeth of rack 135. When the stepping pawl is rocked downward (clockwise in Fig. 7) the ear 153 moves down into the path of travel of the teeth of rack 135, being then spaced therefrom a distance slightly less than half a step. The free end of the stepping pawl 150 overlies a pin 143 carried by the free end of the holding pawl 136, being spaced therefrom a short distance. Thus, the rocking of the stepping pawl 150 to its downward, or operative, position first places the ear 153 in the path of travel of rack 135 and then engages the pin 143 to rock the holding pawl 136 out of blocking engagement with the teeth of rack 135. By this means the multiplier carriage is enabled to take a partial step upon the rocking of the stepping pawl 150, but is prevented from taking a full step by the ear 153. In this position, the tip of the nose 140 will lie below the bottom face of the teeth of rack 135. Then, as the pawl 150 returns to its normal position, the ear 153 moves out of the path of travel of the teeth of rack 135, but spring 138 simultaneously rocks the holding pawl 136 upwardly so that its nose 140 again enters the space between the teeth of the rack, and blocks the rack at the next full ordinal position.

The pawls are operated by the escapement bar 160 which is mounted on the free ends of arms 161, one at the front and another at the back of the keyboard frame. The two arms 161 are pivotally mounted on studs 162 supported by brackets 163 integral with the lower plate 37 of the keyboard frame. It will be recalled that the lateral extension of each of the value keys, excluding "0" but including "9," overlies the escapement bar 160. Thus, depression of any value key, except "0," is operative to depress the bar 160, which rotates around the pivots 162 as a center. The bar 160 extends rearwardly from the keyboard frame to penetrate a slot, or aperture, 154 in the stepping pawl 150. By this means, the depression of any key is operative to rock stepping pawl 150 and holding pawl 136—the downward movement of these pawls per-

mitting a partial step of the multiplier carriage toward the left (right in Fig. 7) and the release of the key and the rise of the two pawls permitting the balance of the step to move the carriage one ordinal space.

Depression of the "0" key is also operative to rock the escapement pawls just described. When the "0" is depressed it engages an arm, not shown, rigidly mounted on shaft 164 rotatably mounted in a pair of brackets 165 integral with the lower plate 37. At its rear end the shaft 164 carries an arm 166, on the outer end of which is riveted a pin 167, also embraced in aperture 154. Thus, the "0" key also operates the escapement mechanism to release the multiplier carriage for a single step to the right.

The depression of the escapement bar 160 is also operative to control the release of the latch member 110 (Fig. 2) to release the ordinally aligned selection rack 100. The mechanism for accomplishing this result is shown particularly in Fig. 2. An arm 170 is pivotally mounted on the bracket 57 by any suitable means, such as screw 171, which is secured to ear 172 of the bracket 57. The forward end of the lever 170 is provided with an upstanding nose 173 which penetrates a slot-like aperture 174 in the base plate 37 of the keyboard frame—the slot being located directly below the escapement bar 160. The nose 173 rises to an elevation immediately below the escapement bar 160, whereby depression of the bar by any of the keys is effective to cause it to engage the nose 173 and rock the lever 170 (counter-clockwise in Fig. 2). The rear end of the lever 170 is pivotally connected to a link 175 by any suitable means, such as pin 176. The lower and rearward end of the link 175, in turn, is pivotally connected to arm 177 by any suitable means, such as stud 178. The arm 177 is pivotally mounted on a bracket, not shown, extending from the left side control plate 23. The upper end of the arm 177 is provided with a nose 179 which lies immediately behind the lower end of the latching lever 110. Thus depression of the escapement bar 160 rocks the lever 170 (counter-clockwise in Fig. 2) which, through link 175, rocks the arm 177 in the same direction. When arm 177 is so rocked, it engages the latching arm 110 and causes it to release the selection rack 100 of the aligned order. The depression of a value key 30 will, by this time, have elevated the proper pin 81 to its operative position to block the rack in the proper differential position.

The mechanism of our invention is particularly adaptable to a "repeat multiply" operation, i.e., one in which a multiplier value can be locked in the selection mechanism so that it may be used for a number of multiplying cycles. When it is desired to use a multiplier factor for a repeated cycle of multiplication, the value is set into the selection mechanism by depression of the keys in order. Thereafter a repeat button 209 (Fig. 1) is pulled to its forward, or operative, position. The button 209 is mounted on a suitable slide 201 (Fig. 4) mounted in brackets 202 on the upper plate 36 of the keyboard frame. The slide 201 is detented in either its operative or inoperative position by any suitable means, not shown. The slide 201 carries a depending projection 203 to the lower extremity of which is riveted a small pin 204. The pin 204 is embraced within a diagonally positioned cam slot 205 in the rearward end of a bent arm 206. The arm 206 is pivotally mounted on the frame plate 36 by any suitable means, such as stud 207 secured to bracket 208. The rearward end of the arm 206 overlies an ear 215 formed on the rear end of a bellcrank 216 which is pivotally mounted on the lower frame plate 37 by any suitable means, such as stud 217 in bracket 218. The depending arm of the bellcrank 216 projects through an aperture, not shown, in the lower frame plate 37, which arm is slotted at its lower end, as at 219.

The bifurcation 219 on the lower end of the bellcrank 216 embraces a pin 226 on the substantially ver-

tical arm of a three-armed lever 225 (Fig. 4). The three-armed lever 225 is pivotally mounted, as on a stud 227 extending to the right from the left-hand control plate 23, as shown in Fig. 5. The forwardly extending arm of the crank 225 is provided with a nose, or single tooth, 228 adapted to cooperate with the teeth 261 of an arcuate rack formed on the free end of a lever 260, as will hereafter be described. The third arm of the crank 225 is pivotally connected at its rear end to two links 229 and 230 by any suitable means, such as pin 231.

The rear end of the link 229 is pivotally connected to a two-armed lever 235, as by pin 236 (see Fig. 4). The lever 235 is pivotally mounted on a transverse shaft 278. The upper end of the lever 235 carries a short stud 237 which is embraced by a slot, not shown, in the lower end of an arm 238 of a bail 239 pivoted on a small shaft 240. The bail 239 has a flanged shoulder 241 lying immediately in front of the selection rack latch 110, and when rocked to its operative condition (clockwise from the position shown in Fig. 4), rises to a point to block rocking of the latch 110. If the latch 110 cannot rock (counter-clockwise in Fig. 4 or clockwise in Fig. 2) as the aligned selection rack 100 is stepped back to its "0" position in the multiplying operation, the rack cannot be latched in an inoperative position. In this event the live tip 114 yields to permit the rack to take the final step to initiate a carriage shift, as described in said patent, but the nose 113 thereof cannot engage the upper edge of the latch arm 110. Therefore, as soon as the multiplier carriage has been stepped one order to the right, which moves the selection rack away from the control of the multiplying mechanism, the rack will immediately return to the value position determined by the elevated pin 81. This value cannot be seen by the operator as the selection rack will then lie to the right of the window 51. Then if, at the end of the multiplying operation, the carriage is permitted to return to the proper ordinal position determined by the set multiplying factor, the racks will remain in their operative position and a second operation can be initiated.

The other link 230 which is pinned to the three-armed crank 225, is bent to extend to the left through an aperture in the control plate 23 (as shown in Fig. 5). At its outer end it is pivotally connected to an interponent 245. This interponent is operated by a member 246 which is translated upwardly at the end of a multiplying operation, simultaneously with the release of a multiplier control key. When the interponent 245 is in effective position, i.e., when rocked by the link 230 upon forward movement of the repeat key 200, it is placed under the left end of the holding pawl 136 (see Fig. 7). Then the movement of the interponent at the end of the multiplication operation, rocks the holding pawl 136 (counter-clockwise in Fig. 7) to release the rack on the multiplier carriage and permit it to be spring-urged by force of spring 127 to an adjusted position, toward the left. Normally the carriage would travel to its extreme left-hand position, but in repeat multiplying operations it is blocked by an ordinal latching means which will now be described.

The latching means just mentioned comprises a bellcrank 250, associated with the lever 125 which connects the power spring 127 to the shiftable multiplier carriage. The bellcrank 250 is pivotally mounted on the screw stud 126, immediately above the lever 125, and is connected to the latter by means of an eccentric bolt 251 embraced within a slot, or aperture, 252 in the bellcrank. Thus, the relative position of the bellcrank 250 and the lever 125 can be adjusted to correct minor inaccuracies of construction. It can be noted that the free end of the bellcrank 250 is formed to provide a latch-releasing hook for releasing a latch mechanism, not shown herein, which holds a multiplier control key depressed throughout a multiplying operation. The hook on the end of bellcrank 250 is effective, when the bellcrank 250 returns to

its home position shown in Fig. 5 (in which position the multiplier carriage lies to the right of the window 51), to release the latch and thereby terminate the operation. A rack lever 260 is associated with the bellcrank 250, and is pivotally mounted on the stud 126. The free end of the rack lever 260 is provided with an arcuate rack 261 which is adapted to cooperate with the latching nose 228 of crank 225. It has been noted that when a constant multiplier factor is inserted in the mechanism, the factor is first inserted in the keyboard (and thence into the pins 81 and selection racks 100) and the repeat key 200 moved forward. Such movement of the key 200 and its associated slide 201 forwardly, rocks the three-armed crank 225 (clockwise in Fig. 4) to cause the tooth, or nose, 228 to engage the rack 261. As the values are inserted in the multiplier mechanism, the carriage will be shifted step-by-step to the left, thereby rocking the bellcrank 250 and rack lever 260 (counterclockwise in Fig. 5). Then, when the key 200 is moved forwardly to engage tooth 228 with the rack 261, the lever 260 is locked in that angular position. The bellcrank 250 and the rack lever 260 are resiliently connected by means of a spring 262 tensioned between an ear 253 on the bellcrank 250 and an ear 263 on the rack lever 260. The rack lever carries an adjustable stop 264 which abuts the front edge of the bellcrank 250, thereby blocking clockwise rotation of the rack lever with respect to the bellcrank.

By the means herein described, the multiplier value is locked in the multiplier selection mechanism by the operation of the repeat key 200, which is effective to lock that value in the multiplier selection mechanism and, at the end of the multiplication operation, to release the holding pawl 136 to permit the multiplier carriage to return to the selected position, by means of the force of spring 127.

It is believed that the operation of the mechanism of our invention will be apparent from the preceding description. However, it can be noted that depression of one of the multiplier keys 30 is effective to rock the associated selection lever 50. The nose 54 of that lever engages the associated pin 81 if the value is between "1" and "8," inclusive, thereby projecting that pin into the path of travel of the ordinarily related selection rack 100. If the value is "9," no pin is projected as the selection rack 100 is permitted to travel until it abuts against a fixed stop 94. If the value is "0," then the selection rack 100 is not released, and no stop pin is necessary. The downward movement of the multiplier value key is also operative to depress the stepping pawl 150 so that its ear lies in the path of travel of the teeth of rack 135 and depresses the holding pawl 136 so that the multiplier carriage is permitted to take a partial step to the left (to the right in Fig. 7) from the force of spring 127. This operation also depresses the bar 160 which bears against the latch releasing lever 170 which, in turn, pulls the arm 177 to operate latch 110, thereby releasing the selection rack 100 for operation. Thereafter the release of the multiplier value key 30 restores the holding pawl 136 and stepping pawl 150 to their original position, thereby latching the multiplier carriage in the next ordinal position.

In our invention, the pins 81 are resiliently biased to their lower, or inoperative, positions and are held in an upper, or operative, position, when lifted by one of the levers 50, by means of the ordinarily arranged latches 88. The latch 88 is operated by movement of a pin 81 from the depression of a value key, by means of the cam portion 85 on the side of the key rocking latch 88, thereby releasing any previously projected pins 81 for return to their inoperative position. The latch 88 is also rocked to its releasing position by depression of the "9" value key, operating through the bellcrank 92 to permit the retraction of pins 81, and thereby permit the selection rack 100 to travel to the stop 94.

In the machine with which our invention is associated, the selection racks 100 are operated upon by the multiplier mechanism, which is operative upon the rack lying in the first, or lowest, ordinal position of the window 31. Normally all of the racks lie to the right of this position. The multiplier carriage is shifted to the left, and the selection racks 100 are thus shifted to the operative position, following the setting of a value in the pin carriage and the operation of the escapement mechanism heretofore described. Thus, values standing in the selection racks 100 to the right of the lowest order shown in the window 31, are of no effect upon the multiplying mechanism. It is therefore unnecessary to restore the racks and pins to an inoperative position, as has heretofore been the case, for values standing to the right of that order are of no effect and, therefore, need not be considered. Thus, only those values set in the last setting operation are effective upon the multiplier mechanism, as all values standing to the right thereof, from a previous operation, can be ignored. When a "9" is inserted in the selection mechanism, the "9" key is operative to release the latch 88, but does not project a pin into the path of travel of the selection 100, thereby permitting it to travel to the stop 94. On the other hand if a "0" is inserted in the selection mechanism, it is operative to control the single operation of the escapement mechanism to step the carriage one order to the left, but is not operative to release the latch 110 so that the selection rack 100 is not affected.

It is obvious that with our invention it is no longer necessary to restore the pins to their inoperative position. This, therefore, permits the elimination of many parts heretofore considered necessary and provides for more efficient assembly of the multiplier unit.

When it is desired to set the multiplier mechanism for repeat operation, the value is inserted in the multiplier keyboard and the repeat key 200 then pulled forwardly. Such operation, as seen in Fig. 4, rocks the bellcrank 216 counter-clockwise and the three-armed lever, or crank, 225, clockwise. This rocking of the lever 225 clockwise projects the tooth 228 thereon into the spaces between teeth of rack 261 on lever 260, thereby locking that lever and setting the mechanism for a return of the carriage to the proper ordinal position. The rocking of the lever 225 also operates the latching bail 239 to prevent operation of the latches 110, thereby preventing the latching of the selection racks 100 in their "0" position. It will be understood, of course, that normally the selection racks are restored to their "0" position by the multiplier mechanism and are latched in that position by the latches 110. If they cannot be so latched, they are free to return under the force of their individual springs to the position determined by the previously set pins 81.

We claim:

1. In a calculating machine having a shiftable pin carriage including a frame, pins movably mounted in said frame and disposed in ordinarily arranged rows, and means resiliently biasing said pins to inoperative position, manually operated means including digit keys for serially shifting said pin carriage and selectively setting said pins one pin in each row, means detenting said pins in the operative position thereof and including latching shoulders on said pins and latching bails extending one along each pin row and engageable with the latching shoulder on any pin set to operative position in the corresponding row, a selection member for each pin row, means resiliently biasing each selection member from an inoperative position thereof to an operative position at which it is stopped by a set pin in the corresponding pin row, latch means releasably engaging and holding said selection members in inoperative position, means controlled by said manually operated means serially releasing said selection member latch means as said pin carriage is serially shifted, and means effective to block reengagement of

said selection member latch means after such latch means have been released.

2. In a calculating machine mechanism comprising a shiftable pin carriage including a carriage frame, a plurality of pins movably mounted in said frame and disposed in ordinarily arranged rows, and means resiliently urging said pins to inoperative position, means releasably detenting said pins in operative position including a latching shoulder on each pin and a latching member disposed adjacent each pin row and engageable with the latching shoulder of any set pin in the corresponding row, manual control means effective to selectively move said pins to operative position, a selection rack associated with each pin row and resiliently urged to operative position as determined by a set pin in the corresponding pin row, latch means associated with each selection rack releasably holding the corresponding selection rack in inoperative position, and means actuated by said manual control means serially shifting said pin carriage each time a pin is set and simultaneously releasing the corresponding selection rack latching means, a live tip on each selection rack engageable by the corresponding latching means, and manually controlled means effective to hold said latching means in position such that said live tips cannot relatch said selection racks upon restoration of said racks to inoperative position after said latching means have been released.

3. In a calculating machine mechanism comprising a shiftable pin carriage including a frame, a plurality of pins movably mounted in said frame and disposed in ordinarily arranged rows, means resiliently urging said pins to inoperative position and means releasably detenting said pins in operative position, manually controlled means effective to selectively set said pins one in each row and serially shift said carriage as the pins are set, selection racks mounted on said pin carriage and associated one with each pin row, means resiliently urging each rack to operative position as determined by a set pin in the corresponding pin row, latch means releasably holding said racks in inoperative position, and means actuated by said manually controlled means serially releasing said latch means as the pins are set in the corresponding pin rows, movable means interposed between said selection rack latch means and the portions of the selection racks opposed thereto, resilient means urging said movable means to position to effect the latching of said selection racks by said latch means, and manually controlled means effective to relatively condition those latch means and corresponding movable means corresponding to the selection racks that have been released by the corresponding latch means against reengagement upon restoration of said racks to inoperative position.

4. In a selection mechanism for a calculating machine, a shiftable pin carriage, pins carried by said pin carriage in ordinarily arranged rows and movable between an inoperative and an operative position, means biasing said pins to inoperative position, manual means effective to selectively move one pin in each row to operative position, ordinal means effective to releasably detent set pins in operative position, means operated by said manual means for momentarily releasing said detenting means to permit restoration to inoperative position of a previously set pin in a row in which a pin is moved to operative position, means controlled by said manual means for ordinarily shifting said carriage, selection racks movable with said carriage and cooperating one with each ordinal row of pins, means biasing each of said racks to turn from a "0" position toward a "9" position, said racks being differentially stopped by set pins in the corresponding rows, latches releasably holding said racks in "0" position, a live tip on each rack adapted to engage the coordinal latch, means biasing each live tip to a position to engage the coordinal latch, and means for blocking the engagement between said live tips and said latches to disable said latches from holding said racks in "0" posi-

tion upon restoration of said racks to said "0" position.

5. In a selection mechanism for a calculating machine, a shiftable pin carriage, pins carried by said carriage in ordinarily arranged rows and movable between an operative and an inoperative position, means biasing said pins to inoperative position, manual means effective to selectively move any pin in each row sequentially to operative position, means controlled by said manual means for ordinarily shifting said carriage, ordinarily arranged selection racks carried by said carriage each engageable with the operative pin of its respective ordinal row of pins, means biasing each rack from a "0" position toward a "9" position, latches for releasably holding said racks in "0" position, a live tip on each rack adapted to engage the coordinal latch when the associated rack is in "0" position, means biasing said live tips to latch engaging position, and means effective to block the engagement of said live tips with said latches and thus disable said latches from holding said racks in "0" position when said racks are restored to such position.

6. In a selection mechanism for a calculating machine, a shiftable pin carriage, pins carried by said carriage in ordinarily arranged rows and movable between an inoperative and an operative position, manual means effective to selectively move any pin in each row sequentially to operative position, means releasably retaining said pins in either operative or inoperative position, means controlled by said manual means for ordinarily shifting said carriage, ordinarily arranged selection racks movable with said carriage each engageable with the operative pin of its respective row of pins, means biasing each rack to turn from a "0" position toward a "9" position, live tips rockably mounted one on each rack, ordinal latches engageable with said tips to releasably hold said racks in "0" position, means biasing said live tips to position to engage the coordinal latches, and means for blocking engagement of said latches by said live tips to disable said latches from holding said racks in "0" position when said racks are restored to such position.

7. In a selection mechanism for a calculating machine, a shiftable pin carriage, pins carried by said carriage in ordinarily arranged rows and movable between inoperative and operative positions, manual means effective to selectively move said pins to operative position in ordinal sequence, means controlled by said manual means for ordinarily shifting said carriage, an ordinarily arranged set of rack members rockably supported on said carriage for movement between two terminal positions and each engageable with a pin of its respective ordinal row of pins which is moved to its operative position, means biasing said rack members toward one terminal position, a set of ordinarily arranged latch members movably mounted on said carriage and effective to respectively latch said rack members in the other terminal position of said rack members, said pins being effective to stop their respective rack member in a differential intermediate position when the rack member is released from the corresponding latch member and one of the pins in the row is moved to operative position, a set of live tips rockably mounted one on each member of one set of members, means biasing said live tips to position to be engaged by the members of the other set of members when said rack members are in said other terminal position, and means effective to disable said live tips from engaging the members of said other set of members and thus prevent latching of said racks in said other terminal position when

said rack members are restored to said other terminal position.

8. In a selection mechanism for a calculating machine, a carriage, selection racks mounted on said carriage for rocking movements about a common axis, a live tip pivotally mounted on each selection rack and extending beyond one end of the corresponding selection rack, and means biasing each live tip to an engaging position relative to said one end of the corresponding selection rack, latches engageable with said live tips to thereby latch the respective racks in one position, means for operating said latches to release their respective live tips and thus enable said racks to be moved from said one position, and means for retaining said latches in their latching position to thereby prevent relatching of said live tips upon return of said racks to their one position or the release of a live tip theretofore held in latched position.

9. In a selection mechanism for a calculating machine, a selection rack member rockable about a predetermined axis between two terminal positions, a latch member rockable about a different predetermined axis and engageable with one end of said selection rack to releasably latch said rack in one of said terminal positions, a pivotally mounted live tip mounted on one of said members and interposed between the said latch and said rack to enable said latch to latch said rack in said one terminal position, and means effective to hold said latch in a position to disable said live tip and thereby prevent relatching of said rack in said one terminal position when said rack is restored to said one terminal position after having been released from said latch.

10. In a selection mechanism for a calculating machine, a pin box containing ordinarily arranged rows of pins having an inoperative and an operative position, means for setting said pins in either an operative or an inoperative position in ordinal sequence, a set of ordinarily arranged selection members movable from one terminal position to engage the operative pin in the coordinal row of pins, resilient means for moving said selection members from said one terminal position toward an extreme operated position, means for restoring said selection members to said first terminal position, a set of ordinarily arranged latch members opposing movement of the coordinal selection members from their one terminal position, a set of live pawls rockably mounted on each member of one of said sets of members, resilient means biasing said live pawls to a position to be engaged by the members of the other of said sets of members when said selection members are in said first terminal position, and means effective to hold said latch members in a position to disable said live pawls from latching engaging the members of the other one of said sets of members and thus prevent latching of said selection members in said first terminal position when said selection members are restored to said first terminal position.
